George Henry Elwell

UNITED STATES PATENT OFFICE.

GEORGE HENRY ELWELL, OF DETROIT, MICHIGAN.

LATCH FOR VEHICLE DOORS.

Application filed May 15, 1919. Serial No. 297,336.

To all whom it may concern:

Be it known that I, GEORGE HENRY ELWELL, a citizen of the United States, residing at Detroit, in the county of Wayne and State of Michigan, have invented certain new and useful Improvements in Latches for Vehicle Doors, of which the following is a specification.

10 My invention relates to improvements in door latches and more particularly to that class of latches employing a bolt for positive engagement with the striker-plate.

15 The objects of my invention are to provide a latch bolt fully adapted to the elasticity of motor car bodies and like uses; to provide a latch bolt operated entirely by spring pressure; and to operate and control the bolt springs by a vertically arranged rotatable shaft, and to provide a latch bolt 20 that may remain fully compressed when the door, to which the latch bolt is attached, is in an open position and may be automatically released when the door resumes a closed position.

25 With these and other objects in view, as will more fully hereinafter appear, the invention consists in certain novel features of construction and arrangement of parts hereinafter described, illustrated in the accompanying drawing and particularly pointed out wherein patentable novelty is claimed for certain features of the device, it being understood that within the scope of what hereinafter thus is claimed various changes 30 in form, proportion, size, and minor details of the construction can be made without departing from the spirit or modifying any of the advantages of the invention.

35 I am aware that in the Letters Patent issued March 17, 1908, No. 882,136, to Frank C. Alltmann certain claims were granted covering a latch bolt operated by a vertically arranged shaft connected therewith, but my vertical shaft, as it will be seen, is 40 not connected with, nor does it engage or operate, the bolt. It merely operates a spring, and the spring operates the bolt.

45 The following is the description of an embodiment of my invention, reference being had to the accompanying drawing:

50 Figure 1 is an upright view of the mechanism of the device;

Figure 2 is a face view of the preceding figure;

Figure 3 is a bottom view of the preceding figure; and

Figure 4 is a side elevation view of a modification of the device.

Referring more particularly to the drawing:

55 Casing 1 is a base-plate having face 2 formed by bending said base-plate, as shown in Figs. 1, 2, 3, and 4. Perforation 3 in said face 2 provides, with the assistance of housing 25, a passageway 4 with proper bearings for bolt 5. Casing 1 is provided with proper bearings for shaft 16 journalled therefo and extending parallel with said face 2 as shown in Figs. 1 and 4. Casing 1 is also provided with perforations 27 and 28 to receive the end of spindle socket post 22 and push-button 18, respectively, as shown in Fig. 2.

60 Bolt 5 is adapted to slide longitudinally in said passageway 4 and capable of projecting its head 6 to a position of abnormal throw beyond the face 2 of casing 1 as shown in Figs. 1, 3 and 4. Said bolt 5 is provided with bent arm 7, as shown in Figs. 1 and 3, as a means of engagement by bolt advancing 65 lever 8 and bolt retracting lever 9.

65 Said levers 8 and 9, preferably lying in the same plane, are journalled to spindle socket post 22 to rotate thereon independently one of the other a limited distance. 70 Flanges 23 with which said levers are provided are formed by bending the metal at right angle to increase the bearings engaging said post and to provide means by which 75 said levers may be held close to their bearings on said post, spring 10 being closely seated around said flanges 23 with its terminals fixed one to each of said levers 8 and 9 as shown in Fig. 1. Said levers 8 and 9 are also provided with arms 30 and 31 respectively intended for engagement by 80 detent mechanism. The normal tension of spring 10 needs only to be sufficient to give said levers 8 and 9 a tendency to close up together and therefore when lever 8 is alone held by the detent mechanism the tension of 85 said spring 10 is in at-rest position as regards its exertion on bolt 5, but when lever 9 is alone held by the detent mechanism

90 95 100

lever 8 exerts a continuous tension against bolt 5 as shown in Fig. 1.

- Spindle socket post 22 is a short shaft having a square perforation extending entirely through it longitudinally and is provided with shouldered terminals forming proper bearings to rotate in perforation 27 in casing 1 and a corresponding perforation in housing 32, as shown in Figs. 1, 2 and 3.
- 10 Said post 22 is also provided with cam-arm 11 extending parallel with said levers 8 and 9 as shown in Fig. 2.

Shaft 16 journaled in casing 1, as already described, is provided with a right angularly bent end 17 to constitute an actuator for levers 8 and 9 so as to swing end 17 to carry bolt advancing lever 8 away from its engagement with bolt 5 and, on the return of said shaft to normal position, to carry lever 9 in the opposite direction. Torsion spring 20 with one terminal fixed to said shaft 16 and the other terminal fixed to casing 1 as shown in Figs. 1 and 4 provides the means for returning said operating shaft to normal position.

- The detent mechanism comprises two catches 13 and 14 each pivoted to casing 1 and maintained in normal position by spring 29 mounted on said casing 1 as shown in Fig. 1. Said catch 13 is adapted to yield to the engagement of arm 30 of lever 8 permitting said arm to pass sufficiently for said catch 13 to return to its normal position barring the return of said arm 30.
- 35 The further continued movement of said arm 30 is adapted to operate and force catch 14 to yield sufficiently to release arm 31 of lever 9 from its interlocked position with said catch 14, and upon the return movement of lever 9 catch 14 is adapted to yield to restore the interlocking engagement between catch 14 and arm 31, as shown in Fig. 1. Catch 13 is provided with arm 19 adapted for operative engagement with beveled arm 24 of push-button 18 mounted in perforation 28 of casing 1 to enable said push-button to be operated as a means to lift said arm 19 to operate catch 13 against the spring tension of spring 29 for the purpose of releasing arm 30 of lever 8 as shown in Figs. 1 and 2. Torsion spring 20 must be of greater strength than spring 10 in order that shaft 16 on its return to normal position may be able to return lever 9 against the tension of spring 10 and also spring 29.

In operation it will be seen that, upon the rotation of shaft 16 when the mechanism is in the position shown in Fig. 1, lever 8 will rotate on spindle socket post 22 until arm 30 has operated both catches 13 and 14 and becomes barred from its return by catch 13 by which lever 8 is held and lever 9 is released. The tension of spring 10 having been increased by this movement of

lever 8, lever 9 upon its release promptly operates bolt 5 to a fully retracted position while shaft 16 is being operated. Upon the return of shaft 16 to normal position, by means of torsion spring 20, lever 9 is carried back to its interlocking engagement with catch 14, but bolt 5 remains in its fully retracted position until, upon closing the door, push-button 18 engages the door-frame or an arm of the striker-plate by which the push-button is operated as the door goes into a closed position, and by this operation the beveled arm 24 of the push-button lifts arm 19 of the catch 13 swinging said catch upon its pivot and away from arm 30 of lever 8 releasing said lever 8 and permitting it to operate bolt 5 to such advanced position as the keeper will allow. A spindle in spindle socket post perforation 12 provides another means for operating the latch. Post 22 may be rotated thereby and cam-arm 11 operating bent end 17 of shaft 16 in the same manner as the operation of said shaft.

A modification of the above construction is shown in Fig. 4. Here the bolt housing 25 includes a housing for coiled main bolt spring 10^B and counteracting bolt spring 10^A. The main spring 10^B being of greater strength than counteracting bolt spring 10^A, it advances bolt 5 against the tension of the lesser spring which is mounted on arm 7 of said bolt and compressed on the forward movement of said bolt by its contact with bar 26 with which the housing 25 of said bolt is provided. Carrier 21 lies between the main body of bolt 5 and main spring 10^B and is moved as a part of said bolt by said main spring until lever 15 pivoted to casing 1 is operated backwardly by shaft 16 in a similar manner as lever 8 in Fig. 1. This movement compresses main spring 10^B, permitting counteracting spring 10^A to operate bolt 5 to a fully retracted position. Lever 15 upon its backward movement is caught and held by detent mechanism comprising spring 29 riveted to casing 1 and provided with catch 13 and push-button 18 which is operated in a similar manner as above described. A spindle socket 12^A of post 22 may operate post 22 so that cam-arm 11^A engages lever 15 and operates it to compress said main spring independently of shaft 16.

Bolt head 6 is preferably of such form as will be only partially received into the keeper so that when the keeper is in normal relative position to the face of the latch casing the bolt will be checked by the keeper on its abnormal advancement and thus maintain a fixed non-rattling engagement between the bolt head and keeper and allow at the same time for variations in relative distance between them as is advantageous in the instance of motor car bodies.

What I claim is:

1. The combination with a door-frame and a door hinged thereto; of a door opening means with which the free edge of the door is provided and normally tending to hold the door open; of means for latching the door to the frame; of spring means to advance and maintain the said second means in latched position only when the door is closed; of manually operative means adapted to compress said spring means independently of said second means; and means to hold in check said compressed spring means when the door is open, said last means being adapted to release said spring means when, by the closing of the door upon said first means said first means is operated from normal position.

2. The combination with a door-frame and a door hinged thereto; of a proper casing; of a bolt slidably mounted in said casing for locking the door in a closed position to the frame; a door opening member with which the face of said casing is provided normally holding the door open; spring means normally adapted to hold the door opening means in normal position; spring actuated means to advance and maintain the bolt in a locking position when the door is closed; means for compressing said bolt advancing spring means and removing its tension from said bolt; detent mechanism for holding said bolt advancing spring means in a compressed position; means for retracting the bolt when said detent mechanism is in detension; and means with which the door opening means is provided for releasing said detent mechanism when said door is closed so that said bolt advancing spring means may reengage and advance said bolt to a locking position.

3. In a latch for vehicle doors the combination with a proper latch casing having a face; of a longitudinally movable bolt slidably mounted in said casing; of a door opening means normally holding the door open; of spring means normally adapted to hold the door opening means in normal position; of spring actuated means to advance and maintain the bolt in a locking position when the door is closed; of means to maintain said bolt in a retracted position when the door is open; of a rotatable shaft, said shaft being mounted on said casing and extending parallel with the face of said casing; and of connections between said shaft and said bolt advancing spring means whereby with the rotation of said shaft the tension of the bolt advancing spring means is removed from said bolt.

4. The combination of a door-frame and a door-hinged thereto; of a keeper for attachment to said door-frame; of a proper casing having a face for attachment to said door; of a bolt slidably mounted in said cas-

ing and provided with a longitudinally elongated head adapted for a full length throw beyond said face; of spring means normally adapted to fully advance said bolt; of manually operative means adapted to compress said spring means independently of any movement of said bolt; of means for retracting said bolt after said spring means has been compressed preparatory to the opening of the door; of means adapted to detain said compressed spring means while the door remains open; and of automatic means adapted to operate said last means and release said spring means and permitting said spring means to engage and advance said bolt throwing said bolt head into said keeper when the door is in a closed position.

5. The combination of a door-frame and a door hinged thereto; of a proper casing having a face for attachment to said door; of a bolt slidably mounted in said casing and provided with a longitudinally elongated head having a nosed end, said head being adapted for a full length throw beyond said face; of a spring adapted to fully advance said bolt; of a keeper for attachment to said door-frame, said keeper being adapted to receive only the nose of said bolt head; of manually operative means for compressing and detaining said spring independently from any movement of said bolt; of means for retracting said bolt after said spring has been compressed and preparatory to the opening of the door; and of automatic means to release said compressed spring upon the closing of the door permitting said spring to reengage and advance said bolt.

6. In a latch for vehicle doors the combination with a proper latch casing having a face; of a bolt slidably mounted in said casing; of means to maintain said bolt in a retracted position; of spring means adapted to advance said bolt; of a rotatable shaft mounted on said casing and extending parallel with the face of said casing; and of connections between said shaft and said bolt advancing spring means whereby with the rotation of said shaft the tension of said bolt advancing spring means is removed from said bolt.

7. In a latch for vehicle doors comprising a latch casing having a face; a bolt slidably mounted in said casing; spring mechanism adapted to exert on said bolt a bolt advancing tension and a bolt retracting tension; a rotatable shaft mounted on said casing and extending parallel with the face of said casing; and connections between said shaft and the bolt advancing spring tension means whereby with the rotation of said shaft the bolt advancing spring tension is removed from said bolt to permit the spring tension in the other direction to automatically retract said bolt.

8. In a latch for vehicle doors the combi-

nation with a proper latch casing; of a bolt slidably mounted in said casing; of spring means adapted to advance said bolt; of means to retract said bolt when said bolt is not engaged by said spring means; of a rotatable shaft mounted in said casing; and of connections between said shaft and said bolt advancing spring means whereby with the rotation of said shaft the tension of said bolt advancing spring means is removed from said bolt permitting said bolt retracting means to operate said bolt to a retracted position.

In testimony whereof I have affixed my signature, in presence of two witnesses.

GEORGE HENRY ELWELL.
